[57] CLAIM

The ornamental design for chair frame or similar article, as shown and described.

DESCRIPTION

FIG. 1 is a perspective view of a chair frame or similar article, showing my new design;

FIG. 2 is a side elevational view, the opposite side being a mirror image thereof;

FIG. 3 is a top plan view;

FIG. 4 is a front elevational view;

FIG. 5 is a bottom plan view;

FIG. 6 is a rear elevational view thereof;

FIG. 7 is a perspective view of a chair frame or similar article, showing a second embodiment of my new design; and

FIG. 8 is a side elevational view of the second embodiment, the opposite side being a mirror image thereof.
